J. A. SMITH.
Organ-Treadles.

No. 137,101.

Patented March 25, 1873.

Inventor.

John A. Smith.

UNITED STATES PATENT OFFICE.

JOHN A. SMITH, OF ERIE, ASSIGNOR TO NEW ERA ORGAN COMPANY, OF
NORTH EAST, PENNSYLVANIA.

IMPROVEMENT IN ORGAN-TREADLES.

Specification forming part of Letters Patent No. 137,101, dated March 25, 1873.

To all whom it may concern:

Be it known that I, JOHN A. SMITH, of Erie, in the county of Erie and State of Pennsylvania, have invented certain Improvements in the Treadles of Organs; and I do hereby declare the following to be a full, clear, and exact description of the same, reference being had to the accompanying drawing and the letters of reference marked thereon, the same forming a part of this specification.

The nature of my invention consists in providing an organ, melodeon, or similar instrument with a treadle so constructed that the same can be as easily operated by persons of low as those of higher stature.

The difficulty with the present construction of the treadles of such instruments is that it is impossible, or at least very difficult, for a child to operate the same while learning to play. To obviate this difficulty is the object of my invention. This I do by so attaching the treadle that it is easily adjusted to any height required.

My invention is shown in the accompanying drawing as follows: Figure 1 is a view of so much of an organ as shows my mode of constructing or attaching the treadles. Fig. 2 is a detached view of some of the parts.

In Fig. 1, A represents the case of the organ, and A' is the projection of the base-board usually made at the place where the treadles attach. C is a bracket, which is usually, or often, placed by the side of the treadles, and B are the treadles. J is the strap or webbing which connects the treadles with the blowers. This, in the drawing, is seen passing from the treadles over the pulley or roller L in the usual manner. The usual manner of attaching the webbing to the treadle is to nail it to the under side of the same near the toe, and the heel of the treadle is hinged to the projecting base A'. In place of this I pass the webbing underneath the whole length of the pedal or treadle B, and finally attach the same to the base-board A', and I place in the toe of the treadle B a roller, M. I also hinge the heel of the treadle on a shaft, H, by lugs or any proper vice. This shaft has its bearings in either of a series of notches, G F E D, which are placed on the inner sides of the brackets C, which series of notches are represented by dotted lines.

In the drawing the primary position of this

shaft H is in the notch G, and the secondary position, that represented by dotted lines, is in the notch D. The shaft and the treadle are thus represented in the extreme positions in which they can be placed. The webbing J, in its passage from the blowers to its place of attachment, passes over the shaft H. When the shaft H and the treadles are raised or lowered the action of the parts on the webbing is the same, only it is exerted at different points. By passing the webbing beyond the toe of the treadle and over the shaft H, and making the same fast at the point named, the elevation or depression of the plane of action of the treadles will be perfectly free. The act of adjusting the treadles to any height is accomplished by a movement of the lever P. This lever is placed midway of the shaft H, and is there firmly attached; from thence it passes, at right angles to the same, directly toward the instrument, before reaching which, however, it turns up at a right angle and terminates at any convenient point directly in front of the operator, but, of course, below the key-board in the handle Q.

The mode of adjusting the pedals is as follows: The handle Q is grasped in the hand and drawn toward the operator, and at the same time it is raised. This action raises the shaft H out of the notch G and carries it up to, say, D. This movement of course carries up the heel of the treadle, and the toe, being sustained on the webbing J by the roller M, is also carried up at the same time—that is to say, the raising of the lever P has carried the treadles up bodily. Now, if the position of the hand as to height be maintained while the handle Q is carried toward the instrument, the whole treadle apparatus is carried forward and the shaft H is carried into the notch D. This operation will place the shaft H into any of the intermediate notches F E D when desired. The roller M is not placed in the position shown for the purpose of acting as a roller except when the treadles are being elevated, and when there may be any slack in the webbing, for if the webbing be perfectly taut no movement of the roller M will take place during the action of the treadles; but if, by stretching or any other cause, the webbing becomes slack, then the roller M will move and prevent wear of the webbing.

The brackets C I expect to make of cast

metal, and the ratchets D E F G will be cast solid therewith and be a part of the same.

My device can be attached to any old instrument, by detaching the treadles and readjusting them to the shaft H, by detaching the webbing from the toe of the treadles and extending it over the shaft H and reattaching it to the base-board A', and by then attaching my ratcheted brackets C and adjusting the shaft H therein.

I do not limit myself to the construction of the ratcheted bracket C as wholly of cast metal, nor as wholly of one piece of material, for it may be made of wood and of wood and iron in separate pieces.

What I wish to claim as new, and to secure by Letters Patent, is as follows:

1. The treadle B, in combination with the

webbing or strap J, constructed, attached, arranged, and operated substantially in the manner and for the purposes shown and described.

2. The ratcheted bracket C, constructed substantially as described, and for the purposes set forth.

3. The ratchets G F E D, in combination with the shaft H and adjustable treadle B, as shown and described.

4. The roller M, in combination with the treadle B and strap J, as shown and described.

5. The lever P, in combination with the shaft H and adjustable treadle B, as shown and described.

JOHN A. SMITH.
